CLAIM

The ornamental design for skin pore cleaner housing, as shown and described.

DESCRIPTION

FIG. 1 is a perspective view of skin pore cleaner housing showing our design;

FIG. 2 is a top plan view thereof;

FIG. 3 is a left side elevation view thereof;

FIG. 4 is a rear elevation view thereof;

FIG. 5 is a front elevation view thereof;

FIG. 6 is a left side elevation view thereof; and,

FIG. 7 is a bottom plan view thereof.

The broken line drawing of a nozzle in FIG. 1 of the drawing is for illustrative purposes only and forms no part of the claimed design.
